UNITED STATES PATENT OFFICE.

JAMES F. TRACY, OF PITTSBURG, PENNSYLVANIA, ASSIGNOR OF ONE-HALF
TO WILLIAM H. McFADDEN, OF ALLEGHENY, PENNSYLVANIA.

ELECTRIC CRANE.

SPECIFICATION forming part of Letters Patent No. 629,936, dated August 1, 1899.

Application filed April 22, 1899. Serial No. 714,036. (No model.)

To all whom it may concern:

Be it known that I, JAMES F. TRACY, a citizen of the United States, residing at Pittsburgh, in the county of Allegheny and State of Pennsylvania, have invented or discovered certain new and useful Improvements in Electric Cranes, of which improvements the following is a specification.

The invention described herein relates to certain improvements in contact-pieces for the trolleys of electric cranes. As is well known, the conductors for the currents for the motors on the trolley-car are arranged longitudinally of the bridge, and the current is taken from such longitudinal wires by means of contact-pieces secured or connected in any suitable manner to the trolley-car, as shown in Fig. 1. These contact-pieces generally consist of metallic blocks having one face grooved for the reception of the conductors and provided with split sleeves, whereby the blocks are secured to a rod attached at its upper end to the car or trolley. By constant rubbing along these conductors these contact-blocks are rapidly worn away and must be replaced. It frequently happens that the upper or one of the intermediate contact-blocks is worn out before the lower ones, but it is necessary in the constructions heretofore used to remove the lower ones before a new one can be substituted for the worn one. This removal and renewal requires considerable time and labor, and the use of the crane is lost for all purposes during such renewals.

The object of the present invention is to provide for the renewal of any one of the operative portions of the contact-pieces without in any way interfering with any of the other contact blocks or pieces or with the operation of the crane, excepting the particular translating mechanism to which the block being renewed conducts the current.

In general terms the invention consists in the construction and combination substantially as hereinafter more fully described and claimed.

In the accompanying drawings, forming a part of this specification, Figure 1 is a side elevation of an electric crane, showing the

usual arrangement of circuits and the manner of connecting the contact-pieces to the trolley-car. Fig. 2 is a view, on an enlarged scale, of the supporting post or rod with my improved contact-pieces secured therein. 55 Fig. 3 is a plan view of one form or construction of my improved contact-pieces, and Figs. 4, 5, and 6 are similar views of various modifications.

In the practice of my invention the supporting rod or arm 1 is secured at its upper end or in any other suitable manner to a trolley-car 2. On this bar or arm are detachably secured the various contact-pieces, the number being dependent upon the number 65 of motors or translating mechanisms on the trolley-car. As clearly shown in Figs. 2 and 3, the contact-pieces are insulated by a sleeve 3, of suitable insulating material, from the supporting-bar. In the construction shown 70 in Fig. 3 the contact piece or block 4, which is formed of suitable metal, has a recess 5 formed in its outer side for the reception of the metal wheel 6. This metal wheel is loosely mounted upon a pin 7, having one 75 end secured to a plate or bridge-piece 8, constructed, as shown in Fig. 3, to extend across the recess 5 and having its ends detachably secured to the abutments or end pieces 9 of the block 4 by screws 10 or other suitable 80 means. The inner or free end of the pivot-pin 7 projects into an opening formed in the rear wall of the recess 5 and is thereby supported. It is preferred that the end pieces or abutments 9 should be grooved for the re- 85 ception of the conductors 11, thereby affording contact area in addition to that presented by the wheel 6. As clearly shown in Fig. 2, the grooved wheel 6 is made of such a diameter that the conductor will be normally supported above the abutments or end pieces 9, which would only come into operation in case of such a wearing down of the wheel as would render the latter inoperative for carrying off the current or the breaking of the 90 pivotal support and the consequent dropping out of the wheel. This block 4 is secured to the supporting bar or arm by means of a split sleeve 12, formed on or secured to the rear side of the block 4 and provided with project- 100

ing lugs 13, through which passes the clamping-bolt 14, whereby the sleeve is tightly drawn around the bar 1. This tightening-bolt also serves as a means whereby the current can be conducted to the motor, the wire for such current being wrapped around the bolt before it is tightened up.

In the construction shown in Figs. 4 and 5 the bridge-piece 8^a is formed integral with the block 4, and the pivotal pin 9^a is removable from the bridge. The pin 9^a can be held in position by means of threads formed thereon and engaging similar threads in the bridge piece or block.

In the construction shown in Fig. 5 the pivot-pin 9^b is held in position by a cotter or pin 15, passing through a boss on the bridge-piece and the pin 9^b.

As shown in Fig. 6, one or both ends of the block 4 may be slotted, forming forks 17, between which wheels 6 are arranged, being loosely mounted on pins 9^c, passing through the forks.

It will be readily understood by those skilled in the art that in any of the constructions shown the contact piece or wheel can be easily and quickly removed and a new one substituted therefor without interfering with any of the parts of the trolley mechanism.

The provision of a grooved block or portion thereof adjacent to the contact-wheel is an essential and desirable feature in the practical use of my improvement, as such grooved portions form auxiliary contact-surfaces, rendering it possible to operate the crane even after the contact-wheel has been broken or worn down. By the use of such auxiliary contact-surfaces the operation of the crane need not be discontinued for the insertion of a new wheel until such time as in the operation of the plant of which the crane forms a part it may be convenient to suspend the use of the crane.

I claim herein as my invention—

1. The combination of a clamping-sleeve, 45 a recessed block carried by the sleeve and a contact-wheel removably mounted in said recess, the block being provided with an additional or supplemental contact-surface arranged at an angle to the axis of the contact-wheel, substantially as set forth.

2. A contact for electric cranes having in combination a block provided with means for attachment to a suitable support, a contact-wheel and a pivot-pin for said wheel detachably secured to the block, said block being provided with additional or supplemental contact-surface adjacent to the wheel, substantially as set forth.

3. A contact for electric cranes having in combination a slotted block provided with means for attachment to a suitable support and having a supplemental contact-surface adjacent to the slot, a grooved contact-wheel and a removable pivot for said wheel, substantially as set forth.

4. A contact for electric cranes having in combination a block provided with a recess in one side, a detachable bridge-piece extending across the recess, a contact-wheel arranged in the recess and a pivot for said wheel secured to the bridge-piece, substantially as set forth.

5. In a crane the combination of a trolley, a standard carried by the trolley, a series of two or more contact-pieces carried by the standard, each of the contact-pieces being removable independent of the other pieces, and supplemental contacts adjacent to the main contact-pieces, substantially as set forth.

In testimony whereof I have hereunto set my hand.

JAMES F. TRACY.
